UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

MANUAL TELEPHONE SYSTEM.

Application filed March 22, 1924. Serial No. 701,211.

This invention relates to manual telephone systems.

In former manual telephone systems, so-called feature cord circuits are provided which function to connect the operator's telephone set automatically to a cord circuit when it is taken for use and for disconnecting this telephone set from this cord circuit, when it no longer needs the attention of the operator. These circuits also control means for automatically signaling the desired station on a party line, when a ringing key has been momentarily depressed to select ringing current of the proper frequency. Other features of these circuits include the extinguishing of all supervisory signals of a cord circuit when it no longer needs the attention of the operator, and in addition certain means function to count automatically, the number of calls answered by an operator. In many of the arrangements now in use, it is necessary to provide a strip of keys for each operator's cord circuit, but in one arrangement now in use a single strip of ringing keys common to all of the cord circuits of an operator's position, control the selection of the proper current to signal a wanted station.

These so-called feature cord circuits require a large number of relays and in accordance with one feature of the present invention it is proposed to replace a number of the relays of such a cord circuit by a progressively movable switch.

Another feature of the present invention relates to the provision of a progressively movable switch to control certain of the functions of a manual cord circuit, in which but one common strip of keys is provided for controlling the connection of a desired one of several frequencies of signaling current to all the cord circuits of an operator's position.

A further feature of the invention resides in the provision of means whereby in a manual telephone system, when two stations on a party line are to be signaled, signaling current of the proper frequency to signal these stations is automatically connected to the party line.

Other features of the invention will appear from the detailed description and the appended claims.

The drawing diagrammatically represents a portion of a telephone system including

the present invention. At the upper left hand corner of the drawing there is represented the substation of a poly-station telephone line of the well known character terminating at the central office in multiple jacks. At the upper right hand corner of the drawing there is represented a substation of a multi-party telephone line likewise terminating in the central office in multiple jacks. Above the dotted lines and in the center of the drawing there is shown a single manual cord circuit, of which each operator is provided with a plurality. Between the dotted lines there is indicated a second and a third cord circuit while below the lowermost dotted line there is shown the equipment common to an operator's position, which includes a single set of frequency selecting ringing keys and relays, as well as an interrupter machine shown at the lower right of the drawing for applying ringing current from the generators indicated in the lower left hand corner of the drawing.

In the drawing there are indicated the elements of a sequence switch, which may be of substantially the same character as the switch shown in the patent to Clement #1,107,153, patented August 11, 1914, although other types of sequence switches may be employed.

The code machine associated with the ringing generators and indicated in the lower right hand corner of the drawing may be of any well known structure in which the various contacts are closed in the same relation as indicated in the diagram. The code machine may consist of a rotating shaft on which there are mounted segments of insulating material to actuate the several sets of springs.

With this brief statement of the apparatus used, it is believed that the invention will best be understood by describing the method of establishing a telephone connection from the substation such as that indicated at A to a wanted substation such as that indicated at B. When the subscriber at A removes his receiver from its switch-hook, the line relay 1 is energized over the two sides of the calling line in series in the well known manner and thereby lights one or more line lamps, such as 2, to signal the various operators that substation A has originated a call. The operator at whose position the cord circuit

2

of this disclosure is located, inserts the answering plug 4 of this cord circuit into a multiple jack of the calling line. This completes an operating circuit through the left hand high resistance winding of relay 6, through the sleeve contacts of the plug 4 and jack 3 in series with the winding of the cut-off relay 5 to ground. The cut-off relay 5 and the operator's barring relay 6 are both energized in this circuit. The cut-off relay 5 disconnects the line relay 1 from the calling line, which relay in turn extinguishes the line lamp 2. The relay 6 on energization closes a locking circuit for itself through its right hand low resistance winding, its right hand front contact and armature and thence over the remainder of the circuit previously described as extending to ground through the cut off relay 5. It will be noted that the operator's barring relay 6 is energized through its high resistance winding and is held operated through its low resistance winding, thereby preventing the energizing of a relay such as 6, at a second operator's position, in case that a second operator connected an answering plug of one of her cord circuits to a multiple jack of the calling line. Also when the operator connects the plug 4 to the jack 3, the answering supervisory relay 7 is energized over the answering end of the cord circuit and over the two sides in series of the calling telephone line. The energization of the relay 7 prevents the lighting of the supervisory lamp 8 at this time. With the relays 6 and 7 operated the motor magnet 9 of the sequence switch is energized in a circuit completed from grounded battery, winding of this magnet, its armature and back contact, sequence switch contact 10 closed in position 1, left hand front contact and armature of relay 7, outer left hand front contact and armature of relay 6, winding of the relay 11 to ground. The motor magnet 9 when thus actuated interrupts its circuit and moves the brushes of the sequence switch to close contacts in position 2. If at this time no other sequence switch is standing in position 5 or 6, the common guard relay 12 will be in its normal position, so that the motor magnet 9 is actuated in a circuit now extending from grounded battery, its winding, armature and back contact, sequence switch contact 13 closed in position 2, back contact and armature of relay 12 to ground. Under the control of this last mentioned circuit, the motor magnet advances the sequence switch into position 3.

If, however, some other sequence switch associated with another cord circuit of this operator's position is standing in position 5 or 6, the sequence switch under consideration will not be moved out of position 2 because at that time relay 12 will be operated. It will be seen that a chain circuit is normally connected to ground through the armature and contact of relay 12, through all of the other sequence switches at this operator's position, so that the operator may "plug up" as many answering cords in advance as she pleases and these calls will be extended to her head set one at a time in rotation.

With the sequence switch of the cord circuit under consideration in position 3, a circuit is completed from ground at the outer armature and back contact of relay 14, left hand winding of the differential relay 15, continuity spring and back contact of relay 16, sequence switch contact 17, closed in positions 3 to 7, conductor 18, back contact and armature of relay 19, resistance 44 to grounded battery. This circuit effects the energization of relay 15 which in turn closes a circuit to ground from the sequence switch contact 20, contact 21 and armature of relay 15, conductor 22, back contact, armature and winding of motor magnet 9 to grounded battery. This circuit is effective to advance the sequence switch from position 3 through position 4 and into position 5. The relay 23 is thereupon actuated from ground, winding of relay 23, sequence switch contact 24 and the right hand winding of the calling supervisory relay 25 to grounded battery. The relays 23 and 25 are energized and the relay 23 connects the operator's telephone set (not shown) over the conductors 26 to the answering end of the cord circuit, so that the operator is now telephonically connected to the calling subscriber and may request the number of the wanted substation such as B. The operation of relay 25 is ineffective at this time.

It will be seen from the foregoing description that only one sequence switch of the cords located at this operator's position can be advanced into position 5, so that the operator's telephone set is connected to one cord circuit only at a time. The operation of the relay 23 extends a circuit from ground through the winding of the slow releasing relay 12, left hand armature and front contact of relay 23, continuity spring and armature of relay 7, and thence to grounded battery through the lamp 8. The energization of relay 12 completes a circuit for operating the meter 27 and since the relay 12 is energized only once for each call answered, this insures an accurate operation of the meter 27. Provision is also made so that this meter may be in readiness to record an "overlap" call, that is, one which is started before the first connection is completed. When the sequence switch of the first connection leaves position 6, the relay 12 releases and moves the sequence switch of the second cord circuit out of position 2 and since this last named sequence switch must be advanced to position 5 before relay 12 is operated again, sufficient time is allowed for the meter to release.

During the time that the operator's telephone set is connected to the answering end of the cord circuit of a connection the guard relay 12 is held operated in a circuit completed through the left hand armature and front contact of relay 23 to grounded battery, either through the continuity spring and armature of relay 7 or through the continuity spring and back contact of this relay 5 and resistance 28. The guard relay holds the meter in its operated position, which insures that no false registration occurs, even though the calling subscriber operates his switchhook and thereby causes the armatures of the supervisory relay 7 to vibrate. The operation of the relay 23 it will be remembered closes a circuit through the supervisory lamp 8 in series with the guard relay 12, so that this lamp is dimly lighted to indicate to the operator to which cord circuit her telephone set is connected. 10

After receiving the number of the wanted line the operator proceeds to test this line, by touching the tip of the calling plug 32 to the sleeve of the multiple jack of the wanted line. If the wanted line is busy this operation causes a distinctive click in the operator's receiver, to indicate that the wanted line is busy. If, however, no click is 15 heard it is the signal to the operator that the wanted line is idle. This testing operation is effected in the well known manner and need not be described further. 20

It should be pointed out that the sequence switch contact 30 is closed in position 1, so that the tip contact of the calling plug is connected to the common busy test key 31 and since all cords not in use are in position 1, the tip contacts are all normally connected to this key, so that the operator can test any line, even though the answering end of the cord circuit is not connected to a telephone line. 25

It is assumed that the wanted line when tested in the manner just referred to, is found idle so that the operator inserts the calling plug 32 into the multiple jack 33 of the called line. This closes a circuit from battery through the right hand winding of the relay 15, the sleeve contacts of the plug 32 and of the jack 33 and thence to ground through the cut-off relay (not shown) of the called telephone line. It will be remembered that at this time the left hand winding of relay 15 is energized so that this relay which is differential in operation now retracts its armatures. This is effective to extend a circuit from ground at sequence switch contacts 34, contact 35 and armature of relay 15, conductor 22, back contact, armature and winding of the motor magnet 9 to grounded battery. Under the control of this circuit the motor magnet advances the sequence switch into position 6, where 30 ring current of the proper frequency to

signal the wanted substation, is selected. In this position the operator's telephone is maintained in connection with the cord circuit by means of the relay 23, which allows the operator to be connected to this cord circuit, after the calling plug 32 is inserted in the multiple jack of the called line and until a ringing key is depressed. In position 6, also the calling supervisory lamp 37 is lighted in a circuit closed at sequence switch contact 360, in order to give a ringing indication. In this position, likewise, the relay 38 is actuated from grounded battery, its right hand winding, conductor 39, outermost back contact and armature of relay 15, sequence switch contact 36 to ground. The relay 38 when operated at its right hand armature and front contact applies ground to conductor 40, whereby the master ringing keys are effective to select the proper ringing current. 35 The control of the conductor 40 at the relay 38 prevents the operation of any of the ringing keys when a sequence switch of a cord circuit is not in ringing position, from being effective. 40

Let it be assumed that the bell at the wanted substation responds only to 50 cycle ringing current. The operator thereupon depresses ringing key 41 to actuate and lock the relay 42 in series with the relay 19, which is also actuated, thereby. Relay 19 opens the energizing circuit through the left hand winding of relay 15, which allows this differential relay to attract its armatures by reason of the circuit which now extends through its right hand winding. With the armatures of relay 15 attracted, it completes a circuit from ground, sequence switch contacts 36 closed in position 6, outermost armature and front contact of relay 15, conductor 22, back contact, armature and winding of motor magnet 9 to grounded battery. Under the control of this circuit, the motor magnet advances the sequence switch to position 7. As the result of this switch leaving position 6, the relay 23 deenergizes to disconnect the operator's telephone set from the cord circuit under consideration and at sequence switch contact 360 opens the lighting circuit for lamp 37. The original energizing circuit of relay 38 is also opened by the operation of the sequence switch, but this relay is now maintained locked from grounded battery through its left hand winding, front contact and armature, back contact and armature of relay 16, sequence switch contacts 43 to ground. At this time also, the motor magnet 9 has its actuating circuit closed from grounded battery, winding, armature and back contact of magnet 9, conductor 22, contact 21 and armature of relay 15, sequence switch contact 20 to ground. It will be noted that the sequence switch contact 20 is closed in positions 7 to 17, so that the last described circuit, unless otherwise 45 50 55 60 65 70 75 80 85 90 95 100 105 110 115 120 125 130

controlled, is effective to advance the sequence switch through positions 7 to 17. However, when relay 42, corresponding to the 50 cycle current, is selected, the sequence switch is stopped in position 12. When the sequence switch reaches this last named position, a circuit is closed from grounded battery, resistance 44, upper armature and front contact of relay 19, inner, upper armature and front contact of relay 42, inner, upper armature and back contacts of relays 45 and 46, conductor 47, sequence switch contact 48, back contact and continuity spring of relay 16, left hand winding of relay 15, outer, back contact and armature of relay 14 to ground. Since both windings of relays 15 are energized at this time, it retracts its armatures and stops the sequence switch in position 12. Fifty cycle ringing current is now applied to the called line from the generator 49 shown in the lower left hand corner of the diagram, conductor 50, contact 51 of the interrupter when cam 52 is rotated through ninety degrees, conductor 53, sequence switch contact 54 closed in position 12, left hand winding of the trip relay 55, left hand back contact and armature of relay 15 through the ring contacts of the plug 32 and the jack 33, over the lower side of the called line, through the ringer at the called station, which it is assumed responds to 50 cycle ringing current, over the upper side of the called line and through the tip contacts of the jack 33 and the plug 32, sequence switch contacts 56 to ground. Ringing current is intermittently transmitted over this circuit under the control of the interrupter 52 until the called subscriber answers, at which time the trip relay 55 attracts its armatures and at its innermost armature and front contact closes a locking circuit for itself through its right hand winding to ground through the sequence switch contact 20. At the middle armature and contact 58 of relay 55, the left hand winding of relay 15 is short-circuited thereby permitting this differential relay to attract its armatures. This operation closes the operating circuit for motor magnet 9, over the conductor 22, armature and contact 21 of relay 15, sequence switch contacts 20 closed in positions 7 to 17. Under the control of this circuit, the motor magnet advances the sequence switch to position 18. This is the talking position and it will be noted that the sequence switch contacts 59 and 60 are closed in this position to complete the conversational circuit. When relay 15 operates it opens the original energizing circuit of relay 16, but it closes a substitute circuit therefore, which is completed at the middle armature and contact 57 of relay 55 to ground, so that the relay 16 is held operated until the sequence switch reaches position 18.

65 Talking battery is supplied to the calling

subscriber through the two windings in series of the answering supervisory relay 7 while talking battery is supplied to the called party through both windings in series of the supervisory relay 25. Conversation 70 may now take place.

At the close of the conversation, when the subscriber at A replaces his receiver on its switchhook, the answering supervisory relay 7 deenergizes and thereby closes a circuit 75 from grounded battery through the answering supervisory lamp 8, back contact and armature of relay 7, outer, left hand, front contact and armature of relay 6, winding of relay 11 to ground. The lamp 8 is lighted in 80 this circuit which is a signal to the operator that the connection is terminated, whereupon she withdraws the answering plug 4 and the calling plug 32 from the jacks with which they were in engagement. If the called 85 party is the first to replace his receiver on its switchhook, the calling supervisory relay 25 deenergizes and thereby completes a lighting circuit for the calling supervisory lamp 37, from grounded battery, through this 90 lamp, right hand back contact and armature of relay 25 and sequence switch contact 62 to ground.

When the sequence switch moves out of position 6 as above described, the sequence 95 switch contacts 36 opens the lighting circuit of the calling supervisory lamp 37 and the relay 23, opens the circuit of the answering supervisory lamp, so that in any of the ringing positions 8 to 17 inclusive, these 100 lamps are not lighted; an arrangement known as the "dark keyboard feature."

If the calling subscriber abandons the call while the operator's head set is connected to the cord circuit shown, that is, while the sequence switch is in positions 5 or 6, relay 14 is not operated. But if the subscriber abandons the call while the sequence switch is standing in positions 7 to 17 inclusive, a circuit is closed from ground at 110 the inner left hand armature and front contact of relay 6, sequence switch contact 63, outermost back contact and armature of relay 7, winding of relay 14 to grounded battery. Relay 14 is thus actuated and closes 115 a locking circuit for itself through its left hand armature and front contact which is independent of the control of the relay 7. Sequence switch contact 63 is closed in position 7 so that the relay 14 can be operated as soon as the sequence switch leaves the listening position, in order that there can be no possibility of the sequence switch stopping in the first ringing position such as 8. If the calling party abandons the call while the sequence switch is in the ringing position, the operation of relay 14 at its outer right hand armature and back contact, opens the energizing circuit for the left hand winding of relay 15, which permits this last 120

named relay to operate by reason of the energizing circuit completed through its right hand winding. An operating circuit for the motor magnet 9 of the sequence switch is now closed over conductor 22, armature and front contact 31, sequence switch contacts 20 closed in positions 7 to 17 inclusive. Under the control of this circuit the sequence switch advances into position 18, where the supervisory lamps are lighted to give a disconnect signal to the operator.

If the calling subscriber terminates the call while the sequence switch is in position 18 and while the called party is connected to the cord circuit relay 14 is not operated, but if the called subscriber has replaced his receiver on its switchhook, a circuit is closed from ground at the inner armature and front contact of relay 6, sequence switch contact 64 closed in position 18, back contact and armature of relay 25, outermost back contact and armature of relay 7, winding of relay 14 to grounded battery. Relay 14 is thus operated and closes a locking circuit for itself in the manner already described.

If the calling subscriber makes a recall by temporarily operating his switchhook to open his line circuit and then maintaining this circuit closed, the lamp 8 is intermittently lighted in a circuit closed from grounded battery, lamp 8, through the middle front contact and armature of relay 7, inner armature and front contact of relay 14 to ground over conductor 65, through an interrupter device (not shown).

Let it be assumed that the called station is located on the same telephone line as the station that originated the call. This kind of a call, as is well known, is referred to as a revertive call. Under such a condition when the calling subscriber initiates a call by removing his receiver from its switchhook, the previously described operations take place, which are effective to advance the sequence switch into position 5, wherein the operator's telephone set is connected to the calling line. The operator then inquires the number of the wanted party and on discovering that the call is revertive, removes the answering plug from the jack of the calling line which is effective to deenergize the relay 6 and thereby advance the sequence switch into position 6 through the contacts 67. In this position the left hand winding of relay 15 is energized in a circuit, which may be traced from ground, outer armature and back contact of relay 14, left hand winding of relay 15, continuity spring and back contact of relay 16, sequence switch contacts 17, over conductor 18, back contact and armature of relay 19, resistance 44, to grounded battery. When relay 15 is thus energized it closes a circuit for advancing the sequence switch into position 7, which circuit includes the

motor magnet 9, conductor 22, outermost front contact and armature of relay 15, sequence switch contacts 36, closed in position 6, to ground. In this instance the sequence switch passes through position 6

70 with the relay 15 energized, so that the relay 38 is not operated. A circuit is now closed

from ground at the right hand armature and back contact of relay 38, right hand armature and back contact of relay 6, inner-

75 most front contact and armature of relay 15, winding of relay 16, sequence switch contact 68, right hand winding of relay 25 to grounded battery.

Relay 16 is thus energized, while the sequence switch is standing

20 in any of its positions 7 to 17. Relay 16

when thus operated extends a circuit from grounded battery, resistance, its armature

25 and continuity spring, left hand winding of relay 15, outer, back contact and armature

of relay 14 to ground. Relay 15 remains

energized to move the sequence switch to

position 18 by a circuit completed through

the motor magnet 9, conductor 22, armature

40 and contact 21 of relay 15, sequence switch

contacts 20 closed in positions 7 to 17 inclusive, to ground. Sequence switch contacts

45 68 are open in position 18, so that the operating circuit of relay 16 is opened and when

this relay retracts its armatures, it breaks

49 the energizing circuit of relay 15, which last

named operation closes an operating circuit

54 for the motor magnet 9, over conductor 22, armature and contact 35 of relay 15, sequence

58 switch contacts 34, closed in positions 18 to

60 20, to ground. Under the control of this

65 circuit, the sequence switch advances into

position 1. The operator now inserts the

70 calling plug of her cord circuit into the jack

75 from which she removed the answering plug

79 of this cord circuit and this functions to

84 energize the relay 15. The energizing cir-

89 cuit is closed from grounded battery through

94 the right hand winding of relay 15, the

99 sleeve contacts of the calling plug 32 and

104 jack 3, winding of the cut-off relay 5 to

109 ground. With relay 15 in its attracted con-

114 dition, a circuit is closed from ground, se-

119 quence switch contact 20 closed in position

124 1, contact 21 and armature of relay 15, con-

129 ductor 22, winding of motor magnet 9 to

134 grounded battery. Under the control of this

139 circuit the sequence switch advances to posi-

144 tion 2, where an operating circuit for the

149 motor magnet is extended through sequence

154 switch contacts 67 closed in positions 2 to 5,

159 inner back contact and armature of relay 6

164 to ground. This circuit advances the se-

169 quence switch to position 6. When the se-

174 quence switch enters position 3, a circuit is

179 completed from grounded battery, resistance

184 44, armature and back contact of relay 19,

189 conductor 18, sequence switch contacts 17,

194 back contact and continuity spring of relay

199 16, winding of relay 15, back contact and

armature of relay 14 to ground. This circuit energizes the left hand winding of relay 15 in opposition to the right hand winding of this relay, so that it retracts its armatures. 5 The operator now depresses two ringing keys such as 41 and 69 corresponding to the ringing frequencies, which will signal the wanted station and the calling station. The depression of these last two keys energizes the relays 42 and 46 in series with the relay 19. These relays when operated are locked in this condition to ground over conductor 40. Relay 19 on operation opens the circuit through the left hand winding of relay 15, so that this relay is energized to complete a circuit over conductor 22, armature and contact 21 of relay 15, sequence switch contacts 20 to ground, for moving the sequence switch into the position through which the proper ringing current is applied to signal the calling and called stations. In this instance the sequence switch must be advanced to position 14. The stopping of the sequence switch in this position is effected by reason of a circuit traceable from ground through the armature and back contact of relay 14, left hand winding of relay 15, continuity spring and back contact of relay 16, sequence switch contacts 70 closed in position 14, innermost front contact and armature of relay 46, back contact and armature of relay 45, inner front contact and armature of relay 42, front contact and armature of relay 19, resistance 44, to grounded battery. This circuit energizes the left hand winding of relay 15 in opposition to its right hand winding, thereby causing this relay to retract its armatures to open the advancing circuit of the motor magnet of the sequence switch. Relay 16 is thereupon actuated from grounded battery, right hand winding of relay 25, sequence switch contact 68, winding of relay 16, innermost armature and back contact of relay 15, sequence switch contact 20 to ground. 40 Ringing current is now applied from the 50 and 66 cycle generators 49 and 73 alternately over conductors 50 and 74. When the interrupter is in such a position that its contacts 71 are closed, the 50 cycle source of ringing current is applied over conductor 76, sequence switch contacts 77 closed in position 14, left hand winding of the trip relay 55, left hand back contact and armature of relay 15, through the ring contacts of the plug 32 and jack 3, over the lower side of the telephone line, through the ringer that responds to 50 cycle ringing current, over the upper side of this telephone line, through the tip contacts of the jack and plug and thence to ground through the sequence switch contacts 56. When the contacts 72 of the interrupter are closed, the contacts 71 of this interrupter are open. The 66 cycle source of ringing current is then applied from generator 73, over conductor 74, interrupter contacts 72 and 75 and thence over the circuit including conductor 76, as previously described, through the ringer at the station that responds to 66 cycle ringing current and thence to ground through the sequence switch contact 56 as previously described. Under the control of these circuits the bells at the two stations referred to, are alternately signaled and when one of the parties answers, the trip relay 55 is operated and locks in the manner previously described, to ground through sequence switch contact 20. At this time relay 16 is energized in series with the right hand winding of relay 25, in a circuit that is completed through contact 57 and middle armature of relay 55. The left hand winding of relay 15 is short-circuited at this time in a circuit closed from grounded battery, resistance, armature and continuity spring of relay 16, contact 58 and armature of relay 55, to ground. Relay 15 thereupon attracts its armatures and at its left hand armature and back contact interrupts the ringing circuit just described. At the contact 21 and armature of relay 15, the operating circuit for the motor magnet 9 is completed over conductor 22, sequence switch contact 20 closed in positions 7 to 17 inclusive to ground. This circuit is effective to advance the sequence switch into position 18, which is the talking position. When the called party answers, the supervisory relay 25 operates and prevents the supervisory lamp 37 from being lighted. Also when the called party answers, the bell at the calling party's station ceases ringing, which is an indication that the called party has answered so that the calling party removes his receiver from its switchhook and conversation then takes place. 45 When both parties to the connection hang up their receivers, the relay 25 deenergizes and lights the supervisory lamp 37. This is a signal to the operator that the connection should be terminated and she thereupon removes the plug 32 from the jack 3. This effects the deenergization of the relay 15, which in turn closes a circuit through sequence switch contacts 34, contact 35 and armature of relay 15 and thence over conductor 22 through the motor magnet 9, which operates to advance the sequence switch into its normal position. 50 In the event that the called party does not answer in the case of such a reverte call, the calling party removes his receiver from its switchhook which is effective to stop the ringing and results in the advance of the sequence switch to position 18. When now the calling party hangs up his receiver the supervisory lamp 37 is lighted in the manner already described to signal the operator for disconnection, whereupon the sequence switch advances into its normal position. 55

tion. In the case last assumed when the calling party removes his receiver from its switchhook, he may intermittently light the supervisory lamp 37 by moving his switchhook up and down. This is a signal to the operator to remove the calling plug and insert the answering plug of a cord circuit into the jack of this calling line. Thereafter the operator may listen-in on the connection and complete it in the manner already described.

What I claim is:

1. In a telephone system, a plurality of telephone lines, a plurality of link circuits, each terminating at each end in a manual switch, a plurality of sources of current for signaling said telephone lines over said link circuits, a ringing key individual to each of said sources of current, said keys being common to said link circuits, and a progressively movable switch for variably connecting said sources of current to a link circuit under the control of said keys, a supervisory signal associated with each link circuit, and means including the progressively movable switch of a link circuit for operating the associated supervisory signal in a distinctive manner in response to the initiation of re-call over said last mentioned link circuit.

2. In a telephone system, a plurality of telephone lines, link circuits for interconnecting said telephone lines, each of said link circuits terminating at each end in a manual switch, a plurality of sources of ringing current for signaling said lines over said link circuits, a single key for each of said sources of ringing current, said keys being common to said link circuits, a progressively movable switch at each link circuit for connecting one of the various sources of ringing current to its link circuit in each of several of its stopping positions, means including said keys for determining the stopping positions of said progressively movable switches, a calling supervisory signal for each link circuit, and means including the progressively movable switch of a link circuit for operating the associated supervisory signal in the course of each call prior to the application of ringing current to said link circuit.

3. In a telephone system, a plurality of telephone lines, a plurality of link circuits for interconnecting said telephone lines, each link circuit terminating at each end in the contacts of a manual switch, a plurality of sources of current for signaling said lines, a key individual to each source of signaling current, said keys being common to said link circuits, a progressively movable switch in certain of its stopping positions connecting a source of current to a cord circuit, a relay having an operating circuit extending through contacts of a link circuit, other means including one of said ringing keys

for controlling said relay in the various positions of said progressively movable switch, and means including said relay for stopping said progressively movable switch in any one of a plurality of positions for connecting a predetermined source of ringing current to a link circuit.

4. In a telephone system, a plurality of party lines, link circuits for interconnecting said lines, each link circuit terminating at each end in a manual switch, an operator's telephone set common to said link circuits, a plurality of sources of ringing current of the proper character to selectively signal the stations on a party line, and means including a progressively movable switch individual to each link circuit for connecting said operator's telephone set to one link circuit at a time and for selectively connecting a desired source of signaling current to said link circuit to selectively signal a party line.

5. In a telephone system, a plurality of telephone lines, each telephone line being provided with a plurality of substations, a plurality of link circuits for interconnecting said telephone lines, each link circuit terminating at each end in the contacts of a manual switch, a plurality of sources of current for selectively signaling the substations on a party line, a key individual to each source of signaling current, a relay individual to and arranged to be operated by each key, said keys and said relays being common to a plurality of said link circuits, a progressively movable switch for each link circuit functioning to connect a different source of signaling current to a link circuit in each of several of its stopping positions, a differential test relay for each link circuit controlling the stopping of its associated progressively movable switch, a primary circuit for said test relay completed through contacts of its link circuit, and a second circuit for said test relay variably controlled by said first mentioned relays.

6. In a telephone system, a plurality of telephone lines, each telephone line being provided with a plurality of substations, a plurality of link circuits for interconnecting said telephone lines, each link circuit terminating at each end in the contacts of a manual switch, a plurality of sources of current for selectively signaling the substations on a party line, a key individual to each source of signaling current, a relay individual to and arranged to be operated by each key, said keys and said relays, being common to a plurality of said link circuits, a progressively movable switch for each link circuit functioning to connect a different source of signaling current to a link circuit in each of several of its stopping positions, a test relay for each link circuit controlling the stopping of its associated progressively

- movable switch, a primary circuit for said test relay extending through a manual contact, and a second circuit for said test relay variably controlled by said first mentioned relays.
7. In a telephone system, a calling telephone line and a called telephone line, link circuits for interconnecting said telephone lines, each of said link circuits terminating at each end in a manual switch, a progressively movable switch individual to each link circuit, an operator's telephone set common to a plurality of link circuits, means including a progressively movable switch of a link circuit taken for use for connecting said operator's telephone set to said last mentioned link circuit, means including a circuit controlled at a plurality of link circuits for preventing more than one progressively movable switch from simultaneously connecting said operator's telephone set to a link circuit, means including a supervisory signal for indicating to which link circuit said operator's telephone set is connected, and means for intermittently operating said supervisory signal for indicating a recall from said calling telephone line while said telephone lines are interconnected.
8. In a telephone system, a plurality of telephone lines, each telephone line being provided with a plurality of substations, the substations of a telephone line being provided with signals responsive to signaling currents of different characteristics, link circuits for interconnecting said telephone lines in pairs, and means under operator's control when two substations of a telephone line are called over a link circuit for automatically and alternately connecting to the link circuit the sources of ringing current of the proper characteristic to signal said stations of said last mentioned line.
9. In a telephone system, a plurality of telephone lines, each telephone line being provided with a plurality of substations, the substations of a party line being provided with signals responsive to signaling currents of different characteristics, link circuits for interconnecting said telephone lines in pairs, means under operator's control when two substations of a telephone line are called over a link circuit for automatically and alternately connecting to the link circuit the sources of ringing current of the proper characteristic to signal said stations of said last mentioned line, and means under operator's control when two substations of a telephone line are called over a link circuit for automatically and alternately connecting to the link circuit the sources of ringing current of the proper characteristic to signal said stations of said last mentioned line.
10. In a telephone system, a plurality of telephone lines, each telephone line being provided with a plurality of substations, the substations of a telephone line being provided with signals responsive to signaling currents of different characteristics, link circuits for interconnecting said telephone lines, and means including a progressively movable switch under operator's control when two substations on the same telephone line are called over a link circuit for automatically and alternately connecting to the link circuit, the sources of ringing current of proper characteristic to signal said substations of said last mentioned telephone line.
11. In a telephone system, a plurality of telephone lines, each telephone line being provided with a plurality of substations, the substations of a telephone line being provided with signals responsive to signaling currents of different characteristics, link circuits for interconnecting said telephone lines, means including a progressively movable switch under operator's control when two substations on the same telephone line are called over a link circuit for automatically and alternately connecting to the link circuit, the sources of ringing current of proper characteristic to signal said substations of said last mentioned telephone line, and means actuated on the response of either of said stations for disconnecting said sources of signaling current from said last mentioned telephone line.

In witness whereof, I hereunto subscribe my name this 21st day of March A. D. 1924.

WINFRED T. POWELL
